(57) **CLAIM**

The ornamental design for a light fixture lens with multi-plane center, as shown and described.

DESCRIPTION

FIG. 1 is a perspective view of the first embodiment which includes center facet lines.

FIG. 2 is a perspective view of the second embodiment which does not include center facet lines.

FIG. 3 is a perspective view of the third embodiment which includes non-sloping side planar sections and center facet lines; and,

FIG. 4 is a perspective view of the fourth embodiment which includes non-sloping side planar sections and no center facet lines.

The broken lines shown in FIG. 1 through FIG. 4 depict environmental subject matter only, and form no part of the claimed design.
